(57) **CLAIM**

The ornamental design for a foldable tool-accommodating device, as shown and described.

DESCRIPTION

FIG. 1 is a perspective view of the foldable tool-accommodating device showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view showing the foldable tool-accommodating device at a folded state.

The broken lines are for illustrating portions of the article that form no part of the claimed design.
